E. W. SYSTROM ET AL.

STACKING BRACE

Filed June 16, 1927

UNITED STATES PATENT OFFICE.

ERNEST W. SYSTROM AND JAY F. WARREN, OF DETROIT, MICHIGAN, ASSIGNEES TO
ROBERT T. ROMINE, OF MOUNT CLEMENS, MICHIGAN.

STACKING BRACE.

Application filed June 16, 1927. Serial No. 199,356.

This invention relates to a stacking brace particularly adapted for use in connection with the piling or stacking of sheet metal at the final operation of a mill or other production source for the purpose of aligning the edges of the sheets as they are successively placed in position to form the pile.

An object of the invention is to provide an apparatus of the above character which is adapted to be placed in fixed relation with respect to a packing table or platform and which is of a portable character so that it may be moved from place to place as desired.

Another object of the invention is to provide the device with means which prevents its accidental tipping or tilting relative to the table as the sheets of metal are slid into position upon the packing table to be aligned one above the other and which likewise serves to prevent any accidental tipping or tilting of the table.

The above and other objects will appear in the following description and appended claims when taken in conjunction with the accompanying drawings.

In said drawings:

Fig. 1 is an end elevation of the stacking brace of our invention.

Fig. 2 is a side elevation of the apparatus of Fig. 1.

Fig. 3 is an end elevation of a modified form of stacking brace.

Fig. 4 is an end elevation of the apparatus of Fig. 3.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also, it is to be understood that the phraseology or terminology employed herein is for the purpose of description and not of limitation, and it is not intended to limit the invention beyond the terms of the several claims hereto appended or the requirements of the prior art.

The apparatus of this invention is preferably employed in connection with the method and apparatus for handling metal shown and described in a co-pending application Serial No. 177,005 filed March 21, 1927. As the

metal sheets issue from the final operation at the mill, they are preferably piled upon a packing table or platform until the requisite number of sheets to form the desired pack or pile have been placed in position thereupon. In order to form a relatively uniform pile we provide at one end of the packing table or platform an apparatus designed particularly for accurately aligning one edge of the sheets as they are successively placed in position upon the table, so that after the requisite number of them have been so placed upon the table, the pile or pack is in readiness to receive the binding apparatus disclosed in the aforesaid application.

The packing table or platform is shown as a whole at A and is provided with relatively short legs A¹ and a flat preferably rectangular floor or supporting surface upon which may be positioned a plurality of spaced transversely extending wood members A². At one end of the table is positioned the improved stacking brace or sheet aligning device of this invention which is shown as a whole at B. The brace B includes, preferably, a pair of horizontal angle bars 10 and a pair of vertical or upstanding angle bars 11 which pairs of angle bars are rigidly connected together by means of a preferably triangular gusset plate 12 which is positioned between the opposed flanges of the several angles 10 and 11. The opposed flanges of the angles and the interposed edges of the gusset plate are secured together by means of rivets or the like 13 to provide a rigid structure. The horizontal angles 10 are adapted to rest upon the floor surface and are detachably connected thereto against accidental relative movement by means of retaining pins or bolts 14. The forward or free flanges 11^a present a flat and unobstructed surface which serves as a stop for the metal sheets of the pack S as they are placed in position flatwise upon the table A.

In order to prevent the stacking brace or sheet aligning device B from tilting as the sheets of metal are slid into position upon the table to be aligned one above the other, and likewise to prevent any accidental tipping or tilting of the table A, we provide a relatively short angle 15 having a vertical flange 15^a and a horizontal flange 15^b. The vertical flange of the angle is secured to the flanges 11^a by means of rivets or the like 16. As shown in Figs. 1 and 2 the angle 15 is se-

cured to the flanges 11^a in such a position that its horizontal flange 15^b will underlie the edge of the platform or supporting surface of the table A and serve as a support for that 5 end of the table. The angle 15 is preferably of a heavier character than the angles 10 and 11 thereby providing a relatively wide horizontal flange 15^b. It will be seen, therefore, that when the successive sheets are slid into 10 position upon the table A, it will be impossible for the stacking brace or sheet aligning device B to tilt relative to the table since the weight of the sheets upon the table is sufficient to prevent this. By providing the retaining pins or bolts 14, any longitudinal or 15 lateral movement of the device B relative to the floor and the table is prevented.

In connection with the handling and aligning of relatively large sheets, it may be found 20 desirable to provide a pair of stacking braces or sheet aligning devices rather than the single device shown in Figs. 1 and 2.

In Figs. 3 and 4 we have shown the use of 25 two such devices each of which is of a construction identical with that shown in Figs. 1 and 2. In this instance an angle bar 150 of sufficient length is provided to interconnect the flanges 11^a of each device B. The vertical flange 150^a is secured to the flanges 11^a 30 by means of rivets 160 and it will be noted that the horizontal flange 150^b underlies the edge of the floor or supporting surface of the table A when the stacking braces are in fixed relation with respect to the table.

35 It will be understood, of course, that the wood blocks A² in position upon the table A may be omitted and the sheets which form the pack S placed in position directly upon the floor or supporting surface of the table.

40 From the foregoing it will be understood that the flanges 11^a of the braces B in the form of the invention shown in Figs. 1 and 2 and the similar flanges of the pair of braces B shown in Figs. 3 and 4, serve as a stop or abutting surface for the edges of the sheets as they 45 are placed in position upon the table A. By sliding the successive sheets into engagement with the flanges, a pile or pack of metal will be formed with the edges of the sheets there- 50 of in strict vertical alignment. Moreover the impact of the sheets against the bars 11 will not result in displacing the stacking brace due to the retaining angle bar 15 extending beneath the stacking table.

55 We claim:

1: A stacking brace for aligning metal sheets when stacked on a table or platform, comprising an upright member adapted to abut against a side edge of the table, and an 60 angle secured to said member and having a horizontal flange adapted to extend beneath the floor of the table in engagement therewith.

2: A stacking brace for aligning metal sheets when stacked on a table or platform, 65 comprising an upright member having a flat

face adapted to abut against a side edge of the table, and an inverted angle secured to said member and having a horizontal flange adapted to extend beneath the floor of the table in engagement therewith. 70

3. A stacking brace for aligning metal sheets when stacked on a table or platform, comprising a pair of vertical angle bars positioned back to back and having oppositely extending flanges lying in the same plane and 75 adapted to be positioned at the edge of the table, and an angle secured to said flanges and having an out-turned horizontal flange adapted to project beneath the floor of the table to prevent tilting of said brace. 80

4. A stacking brace for aligning superposed metal sheets, comprising a substantially L-shaped metal frame, a gusset plate connected with said frame for bracing the same, and an angle carried by said frame for 85 engagement with the under side of a packing table.

5. A device for aligning the edges of metal sheets placed flatwise upon a packing table or support, comprising a pair of horizontal 90 angles providing a base for said device, a pair of upright angles connected with said horizontal angles, a gusset plate connected with both pairs of angles for reinforcing and bracing the device, and means carried by said upright angles for engagement with said packing table to prevent relative tilting movement 95 of the device and table.

6. A portable device for aligning the edges of metal sheets placed flatwise upon a packing 100 table or support, comprising a pair of horizontal angles providing a base for said device, a pair of upright angles connected with said horizontal angles, a gusset plate connected with 105 both pairs of angles for reinforcing and bracing the device, and an angle member carried by said upright angles for engagement beneath said packing table to prevent relative tilting movement of the device and table. 110

7. A device for aligning the edges of metal sheets placed flatwise upon a packing table or buck, comprising a pair of horizontal angles providing a base for said device, a pair of upright angles connected with said horizontal 115 angles, a gusset plate connected with both pairs of angles for reinforcing and bracing the device, means carried by said upright angles for engagement beneath said packing table to prevent relative tilting movement 120 of the device and table, and means carried by said horizontal angles to prevent relative shifting movement of the device upon the floor. 110

8. In an apparatus for forming packs or 125 piles of sheet metal, the combination of a packing table for receiving the sheets, a stacking brace comprising spaced upright members adapted to be positioned at one end of said table, and means for interconnecting 130

said members and for engaging the table to prevent the accidental displacement of said members by impact of the sheets.

9. In an apparatus for forming packs or piles of sheet metal, the combination of a packing table for receiving the sheets, a stacking brace comprising spaced upright members adapted to be positioned at one end of said table, and a horizontal angle bar connecting said members together and having a horizontal flange adapted to project beneath the floor of the table and cooperate therewith to prevent displacement of said members by impact of the metal sheets.

10. A stacking brace for aligning metal sheets when stacked on a table or platform, comprising an upright member adapted to project above the table and to abut against a side edge thereof, and a member carried by said upright member and extending freely beneath the said edge of the table in engagement therewith to prevent displacement of said upright member by impact of the sheets.

In testimony whereof we affix our signatures.

ERNEST W. SYSTROM.
